UNITED STATES PATENT OFFICE.

WILHELM GENSECKE, OF HOMBURG, GERMANY.

OXYGEN APPARATUS.

Application filed December 4, 1922. Serial No. 604,836.

To all whom it may concern:

Be it known that I, WILHELM GENSECKE, a citizen of the German Republic, and residing at Homburg vor der Hohe, Homburgerstr. 87, Germany, have invented certain new and useful Improvements in Oxygen Apparatus, of which the following is a specification:

- This invention relates to an oxygen apparatus for facilitating breathing for crews of air-craft such as aeroplanes, dirigible and non-dirigible balloons, and it can also be employed whenever more and more oxygen is to be supplied as the altitude increases.
- 10 The oxygen destined for breathing purposes is produced in a known manner by evaporating liquid oxygen stored and conveyed in a Dewar flask whose contents are isolated to prevent the penetration of heat.
- 15 The evaporation is brought about by forcing by pressure produced in the Dewar vessel the required quantities of liquid oxygen through a pipe, whose end is submerged in the liquid, into an evaporating vessel heated by the atmosphere, wherein the liquid oxygen is evaporated.
- 20

The principal problem to be solved in apparatus of this kind is that the smallest possible quantity of oxygen shall be discharged when the apparatus is at ground level and until a certain altitude is reached, or at any rate the oxygen given off should not be more than the amount which is lost on account of its being impossible to provide an absolutely perfect heat insulation. Furthermore the quantity of oxygen given off at a certain altitude should always be the same, and it should increase as the altitude increases.

In accordance with the invention this is accomplished by automatically producing at a certain altitude a difference of pressure between the space in the interior of the Dewar vessel and the chambers connected therewith on the one hand, and the breathing pipe on the other hand, this difference of pressure increasing automatically as the altitude to which the apparatus is raised is increased. The discharge of the oxygen into the breathing pipe takes place through a nozzle.

The invention is illustrated in the drawing in which Fig. 1 is a sectional elevation of the entire apparatus,

Fig. 2 is a section through a valve chamber and the automatic valve controller,

Fig. 3 is a graphical representation of at-

mospheric pressures and the pressures in the flask and

Fig. 4 illustrates the quantities of oxygen discharged at various altitudes.

In Fig. 1 a vessel *a* containing liquid oxygen and isolated against heat from without is shown. To evaporate the oxygen it is forced by pressure through the partly submerged pipe *b* into the evaporating vessel *c* where it is evaporated and thereupon passes through the nozzle *d* into the breathing pipe *n*. The greater the difference between the pressures in the flask and the atmosphere, the greater the quantity of the oxygen discharged through *n* will be. The device *e* attached to the top of the vessel is the most important part of the invention inasmuch as it automatically produces the required difference of pressure after a certain altitude is reached and alters this pressure difference as the altitude changes.

The operation of the device will be explained more fully with reference to Fig. 2. Joined to the Dewar vessel by a gastight screw connection is a hollow cylindrical chamber *f* which communicates by openings *h* with the interior of the Dewar vessel. The chamber *f* may be closed or opened to the atmosphere by means of a conical valve *k*. The valve *k* is controlled by one or more diaphragms located in the interior of the chamber *f*. These diaphragms consist of corrugated metal plates and are the walls of boxes similar to the capsules which are employed in aneroid barometers. The interior of the capsules is entirely closed to the exterior and preferably evacuated, although any desired pressure may exist in the capsules.

When the pressure in the chamber *f* alters, the diaphragms *i* tend to distend or contract.

When the oxygen vessel is at ground level the conical valve *k* is adjusted so as to be open, so that the pressure in the interior of the oxygen vessel is equal to the pressure of the atmosphere. When the vessel is elevated to higher altitudes the diaphragms in the chamber *f* distend axially on account of the reduced air pressure. At a certain predetermined height the axial expansion of the capsules *i* is such that the valve *k* is closed, so that the pressure in the interior of the vessel *a* rises above that of the atmosphere due to the natural evaporation of the liquid oxygen. As the altitude increases the pres-

sure produced in the interior of the vessel by the actuation of the valve *k* through the action of the diaphragms will remain approximately constant. But as the pressure of the external atmosphere drops as the altitude increases, the pressure difference between the internal and external spaces will continually increase, whereby the desired increase of the quantity of oxygen discharged through the nozzle *d* is obtained. In order to also turn to account the small quantity of oxygen that is continually discharged by the unavoidable evaporation in the interior of the Dewar vessel, the pipe *m* 15 may be connected with the breathing or receiving pipe *n*.

The operation of the device is graphically represented in Figs. 3 and 4. In Fig. 3 the atmospheric pressure is represented as a function of the altitude. The pressure in the flask, which remains practically the same from a certain altitude, is shown at A, and the pressure difference obtained at different altitudes is represented by the hatched surface. Fig. 4 indicates the quantities of oxygen discharged. Up to the point B only the small amount of gas resulting from unavoidable evaporation is discharged. From B on this quantity increases under the influence of the increasing pressure difference until the maximum shown at C is reached.

I claim:

1. Apparatus for controlling the gasification of liquid oxygen under varying atmospheric pressure comprising a container for the liquid oxygen, an orifice in the container communicating with the atmosphere, a valve in said orifice, said valve being open under normal atmospheric pressure, and means 35 tending to close said valve under decreasing atmospheric pressure.

2. Apparatus for controlling the gasifica-

tion of liquid oxygen under varying atmospheric pressure comprising a heat insulated container for the liquid oxygen, an 45 orifice in the container communicating with the atmosphere, a valve in said orifice, and a drum for controlling said valve.

3. Apparatus for controlling the gasification of liquid oxygen under varying atmospheric pressure comprising a heat insulated container for the liquid oxygen, a chamber having an outlet into the atmosphere, communicating means between the chamber and the container, a valve in said 55 outlet, a plurality of capsules with distendable and contractible diaphragms for controlling said valve, whereby a substantially constant pressure is maintained in the container and the chamber, and an exit conduit 60 for the oxygen in connection with the container.

4. Apparatus for controlling the gasification of liquid oxygen under varying atmospheric pressure comprising a heat insulated container for the liquid oxygen, a chamber having an outlet into the atmosphere, communicating means between the chamber and the container, a valve in said outlet, a plurality of capsules with distendable and contractible diaphragms for controlling said valve, whereby a substantially constant pressure is maintained in the container and the chamber, an exit conduit for 65 the oxygen in connection with the container, 70 and communicating means between said chamber-outlet and said exit conduit.

In testimony whereof I affix my signature in presence of two witnesses.

WILHELM GENSECKE.
